UNITED STATES PATENT OFFICE.

ERNEST M. WHITE, OF DETROIT, MICHIGAN.

SPLASH-TROUGH.

1,184,804.

Specification of Letters Patent. Patented May 30, 1916.

Application filed October 27, 1915. Serial No. 58,295.

To all whom it may concern:

Be it known that I, ERNEST M. WHITE, a citizen of the United States, residing at Detroit, in the county of Wayne and State 5 of Michigan, have invented a new and useful Splash-Trough, of which the following is a specification.

This invention relates to means designed to be attached to the inner wall or walls of 10 a crank case of an internal-combustion engine provided with a series of cylinders and a main oil receptacle for the purpose of receiving a portion of the lubricating oil that is splashed up from each of the small auxiliary receptacles in the bottom of the crank case by the ends of the connecting rods and conveying that oil to the next auxiliary receptacle in the rear or to the main receptacle; and the object of this invention is to 15 provide an efficient oil conveyer of this character that can be readily secured in position and that may be produced at low cost.

This invention consists in a series of oil troughs combined to form a separate unit 20 adapted to be secured to one side of the lower portion of a crank case of a common type of internal-combustion vehicle engine so that the oil splashed up by the connecting rods from small reservoirs in the bottom 25 of the crank case will be carried rearwardly step by step to a main reservoir below the fly-wheel and formed by the fly-wheel housing, and thus prevent an excessive accumulation 30 of lubricating oil, especially at the front end of the crank case when the vehicle 35 is going down hill and thereby avoid over-lubrication of the cylinders but especially of the front cylinder and the excessive deposit of carbon therein.

In the accompanying drawings, Figure 1 40 is a side elevation of a four-cylinder internal-combustion engine with a portion of the crank case broken away. Fig. 2 is an elevation of my improved splash trough secured in position. Fig. 3 is a transverse section of the lower part of the crank case. Fig. 4 is a front elevation of the splash trough. Fig. 5 is a transverse section, through a modified form thereof. Fig. 6 45 is a perspective of one end of the reinforcing bar for the bottom portion of the crank case. Fig. 7 is a side elevation of a modified form of splash trough secured in proper position. Fig. 8 is a plan of the same. Fig. 9 50 is an end elevation of this trough. Fig. 10

is a section on the line 10—10 of Fig. 8 on a larger scale. Fig. 11 is a perspective of a templet by means of which the holes for the securing bolts for the troughs may be located.

Similar reference characters refer to like parts throughout the several views.

The engine shown in Fig. 1 is of well known construction, being used on the Ford cars, and has a block 1 of cylinders united 55 to the upper crank case 2. The lower crank case 3 is preferably of pressed sheet metal secured to the upper case by means of bolts 4. The crank shaft 5 has cranks 6, 7, 8, 9, 10 and 11 which receive thrust from the 60 lower ends of connecting rods 13, 14, 15 and 16. These connecting rods have downwardly extending bolts 17 and nuts 18 adapted to dip into lubricating oil in the 65 small receptacles 19, 20 and 21 in the cover 22 of the lower crank case, which cover is held in place by means of screws 24 that are threaded into the lower cover reinforcing 70 bar 25. A gasket 26 is usually placed between the lower case and cover.

The rear ends of the upper and lower cases are expanded to make room for the fly-wheel 27, magnet carrier 28 and the stationary magnet support 29, shown conventionally in Fig. 1, and also to constitute the 75 main oil receptacle 30. It has been found that when the engine is running, a heavy mist of oil fills the entire case, and that this mist is much heavier at the rear end than at the front end when the vehicle is moving. 80

An oil pipe 32 extends into the magneto support and is provided with a funnel 33 to receive the oil that is carried up by the fly-wheel 27 and the magnet carrier, and this oil flows to the front end of the lower case 85 and into the front auxiliary receptacle 19, whence it is splashed up against the walls of the case and into the bore of the forward cylinder by means of the connecting rod 13. When the vehicle runs on a level road, the 90 oil fills the lower case up to the top of the reinforcing bar 25, which results in excessive lubrication of the cylinders. The oil finally runs over the rear transverse portion of this bar into the main oil receptacle 30.

When the vehicle runs down hill, the front end of the case fills with oil and an excessive quantity is splashed up by the connecting rod 13, causing excessive lubrication of the front cylinder while the third auxiliary 95

receptacle may be almost dry and the third and fourth cylinders receive too little lubrication. The excess of lubricant in the front cylinder is burned and causes an undesirable deposit of carbon at the spark plugs and valves, while under-lubrication of the rear cylinders may result more seriously.

The present invention is embodied in means for preventing excessive accumulation of lubricating oil in the case, especially at any particular point thereof beneath the cylinders, by conveying this oil toward the rear and into the main receptacle.

The preferred form consists of a resilient sheet 35 of suitable metal, secured in place by means of bolts 36, the nuts 37 being on the outside and small lips 38, struck up from the sheet 35, being employed to prevent the bolts from turning. This sheet is formed with troughs 39 which slope downwardly toward the rear so that the oil splashed up out of the auxiliary receptacle 19 will flow to the auxiliary receptacle 20, and so on until at the rear end, the oil will be conducted to the main receptacle 30. If there were no troughs to conduct the oil splashed up by the connecting rod 15 over and beyond the rear transverse portion of the reinforcing bar 25, the troughs between the receptacles 19 and 20, and between the receptacles 20 and 21 would be ineffective as the oil would stand above the bottom of the cover 22 and immediately flow forward from one auxiliary receptacle to the other. But by conducting the oil splashed up by the connecting rod 15 to the main receptacle 30, the excessive lubrication because of the depth of oil above the cover 22 is entirely avoided, and a continuous flow of oil to the main receptacle in the rear is produced.

The sheet 35 is preferably made of sufficient length to extend from opposite the front receptacle 19 to or just beyond the rear edge of the transverse portion of the reinforcing bar 25, so that the oil will flow into the main receptacle 30. It may be held in position by being formed a trifle flatter than shown in Fig. 3, and then be drawn down to final position by means of the bolts 36. Or small fingers 41 (Fig. 5) may be secured to the sheets so that their lower ends will extend down behind the reinforcing bar 25. Or small brackets 42 of sheet metal (Fig. 4) may be secured to the sheets and fit the reinforcing bars.

In order to position the holes for the bolts 36, a templet 45 such as shown in Fig. 11 may be employed. The cover 22 being removed, the templet secured in position on the outside of the lower case by means of the screws 24 passing through the holes 46 and into their regular holes in the bottom case 3 and bar 25. The holes for the bolts 36 may then be marked through the holes 47 in the templet, or the templet may be

employed as a jig, as well, for guiding the drill.

In some cases it may be desirable to employ a set of troughs embodying the present invention in the form of a casting of 70 considerable stiffness. In Figs. 7, 8, 9 and 10, I have shown a series of troughs 50, 51 and 52, the troughs 50 and 51 having inwardly extending discharge ends 53, while the rear troughs 52 extends just above the 75 reinforcing bar 25. This structure may be held in position by screws 54, whose proper positions may be determined by a templet 45. It will be understood that these troughs 80 may be secured to both sides of the crank case, as indicated in Fig. 3, and that the length may be varied so as to adapt this invention to engines of any number of cylinders, so long as a main oil receptacle 85 has an oil receiving portion or opening at the discharge end of these troughs. It will be understood that this present invention does not include the location or structure 90 of the main oil receptacle, which may be of any desired form located in any convenient position.

I claim: —

1. In a multi-cylinder engine, the combination of a crank case formed to constitute a main oil receptacle and a series of 95 aligned auxiliary oil receptacles into which the lower ends of the connecting rods may dip to splash the oil out of said troughs, means for elevating the oil from the main receptacle and conducting it to an end auxiliary receptacle, a sheet metal plate secured to a side of the crank case and formed with troughs for conveying the oil thus splashed up to adjacent auxiliary receptacle and to the main receptacle. 105

2. In a multi-cylinder engine, the combination of a crank case having a removable closure provided with auxiliary oil receptacles and having a main oil receptacle adjacent one of the auxiliary receptacles, and 110 a sheet metal plate secured to a side wall of the crank case and provided with troughs inclined downwardly toward the main receptacle.

3. A new article of manufacture consisting of a sheet metal plate formed with troughs inclining downwardly toward one end and adapted to be secured to the inner side wall of the crank case of an internal combustion engine to convey lubricating oil 115 longitudinally of the crank case.

4. In a multi-cylinder engine, a lower crank case having a central opening, a closure for the opening provided with a series of depressions to serve as auxiliary oil receptacles, a reinforcing bar within the crank case surrounding said opening and said receptacles, said crank case being formed with a main oil receptacle on the outer side of 125 said reinforcing bar, and inclined troughs 130

secured to the wall of the crank case and discharging oil splashed up from said auxiliary receptacles beyond said reinforcing bar into said main receptacle.

5. In a multi-cylinder engine, a lower crank case and a bottom therefor having main and auxiliary oil receptacles, a removable structure mounted within the crank case along one side wall and embodying a series of troughs inclined downwardly toward the main oil receptacle, and bolts extending through the wall of the crank case to secure the troughs in position.

6. In a multi-cylinder engine, a lower crank case and a bottom therefor having main and auxiliary oil receptacles, a removable structure mounted within the crank case along one side wall and embodying a series of troughs inclined downwardly toward the main oil receptacle, bolts extending through the wall of the crank case to secure the troughs in position, and means mounted on the removable structure to prevent the bolts from turning.

25. 7. In a multi-cylinder engine, a crank case formed with a main oil receptacle and having its bottom provided with a series of depressions to serve as auxiliary oil receptacles, a cross bar extending across said crank case between the main receptacle and the auxiliary receptacles, and inclined troughs secured to the wall of the crank case and discharging oil splashed up from said auxiliary receptacles beyond said bar 35 into said main receptacle.

8. In a multi-cylinder engine, a crank case formed with main and auxiliary oil receptacles, a removable structure mounted within the crank case along one side wall and embodying a series of troughs inclined downwardly toward the main oil receptacle, bolts to secure the structure in position, and means on said structure to prevent the bolts from turning.

45. 9. A new article of manufacture consisting of a substantially rectangular sheet metal plate having inclined troughs formed thereon by expanding the metal, and adapted to be secured within the crank case of 50 an internal combustion engine to convey lubricating oil longitudinally thereof.

10. A new article of manufacture con-

sisting of a sheet of metal formed with ridges which constitute troughs when the sheet is placed in inclined position, said 55 troughs inclining downwardly toward one end, said sheet being adapted to be secured within the crank case of an internal combustion engine to convey lubricating oil longitudinally thereof. 60

11. In a multi-cylinder engine, a crank case formed with a series of auxiliary oil receptacles and a main oil receptacle all in alignment and separated by intermediate portions of the crank case which are substantially in the same plane, an oil conveyer consisting of a sheet of metal formed with troughs, which sheet extends along the receptacles in the crank case and inclines upwardly away from them, all of said troughs 70 formed on the sheet being inclined downwardly toward the main oil receptacle.

12. In a multi-cylinder engine, a crank case provided with aligned main and auxiliary oil receptacles, a removable structure 75 mounted within the crank case along one side wall and embodying a series of troughs inclined downwardly toward the main oil receptacle, and means to secure the troughs in position.

13. A new article of manufacture consisting of a sheet of metal adapted to be mounted within the crank case of an internal combustion engine having oil receptacles in its crank case bottom, and which sheet of 85 metal is adapted to be secured along one wall of the crank case so as to incline downwardly toward the bottom to conduct the splashed-up lubricating oil back into oil receptacles in said bottom. 90

14. In a multi-cylinder engine, a lower crank case provided with a main oil receptacle and a series of auxiliary oil receptacles, means to convey the oil from the main oil receptacle to one of the auxiliary 95 oil receptacles, and an oil conveyer mounted in said crank case adjacent one wall thereof and embodying troughs inclined downwardly to carry the oil splashed up out of said auxiliary oil receptacles to other 100 oil receptacles.

In testimony whereof I sign this specification.

ERNEST M. WHITE
